PULSE CONTROL SYSTEM

**Donald E. Norgaard, Schenectady, N. Y., assignor
to General Electric Company, a corporation of
New York**

Application December 9, 1942, Serial No. 468,406

5 Claims. (Cl. 250—27)

1

My invention relates to systems for generating and controlling alternating current signals, particularly to systems for supplying to a suitable utilization circuit alternating current signals whose polarity and amplitude vary correspondingly with a direct current input control potential, and the object of the invention is to provide a simple and improved system which operates especially efficiently in supplying, to an output circuit, square waves of low and medium frequency and any desired percentage of width, and wherein no current drain is required from the source of direct control potential.

In accordance with the present invention this object is attained by the provision of a translation circuit comprising means, the components of which are all stationary, to supply alternating current to an output circuit having the frequency of a reference alternating input potential, and means included in the translation circuit to reverse the phase of the output current in response to the magnitude of a control unidirectional input potential. The translation circuit includes an electron discharge device upon the control electrode of which the unidirectional control potential is impressed and in the anode-cathode circuit of which a potentiometer is included, a second electron discharge device being provided for determining the periods of operation of the first discharge device, thereby to initiate pulses in its anode-cathode circuit. Upon the control electrode of the second discharge device potentials are impressed from the source of alternating reference potential, and a portion of the potentiometer is included in the anode-cathode circuit of the second discharge device.

The novel features which are considered to be characteristic of my invention are set forth with particularity in the appended claims. My invention itself, however, both as to its organization and method of operation together with further objects and advantages thereof may best be understood by reference to the following description taken in connection with the accompanying drawing wherein Fig. 1 is a diagrammatic representation of a circuit embodying the invention; Fig. 2 shows a curve representing the alternating reference potential; and Fig. 3 shows curves of output alternating potential obtained from the system and corresponding to a range of values and polarities of the unidirectional input control potential, for example, to zero input potential or to a given positive or negative potential value.

In Fig. 1 a translation circuit in accordance

with my invention is shown comprising electron discharge devices, designated **V**₁ and **V**₂, arranged to be supplied with anode current from a common source (not shown), the anode-cathode circuits of the discharge devices including a common cathode resistor **1**. A source (not shown) of variable uni-direction control potential is connected to the control electrode-cathode circuit of discharge device **V**₁ and a source (not shown) of alternating reference potential is connected to the control electrode-cathode circuit of discharge device **V**₂ through a capacitor **2**. The anode-cathode or output circuit of device **V**₁ includes, in series therein, a potentiometer **3** or equivalent impedance element to the opposite terminals **4** and **5** of which any suitable alternating current utilization circuit (not shown) may be connected through a capacitor **6**.

The system in accordance with my invention
20 may be utilized, for example, for controlling, in
response to the amplitude and polarity of the uni-
directional potential supplied to discharge device
V₁, the speed and direction of rotation of a motor.
However, various other utilization circuits may be
25 employed in connection with the system, and
controlled in response to the unidirectional poten-
tial.

30 For a purpose to be explained hereinafter, a portion of the potentiometer 3 is connected in series in the anode-cathode circuit of device V₂ by connecting the latter circuit to the potentiometer at a given point, as 7. One section, as 8, of the potentiometer is therefore included in the anode-cathode or output circuit of device V₂ and both sections, 8 and 9, are included in the anode-cathode or output circuit of device V₁. A leak resistor 10 is preferably provided connected across the control electrode-cathode circuit of discharge device V₂.

40 The alternating potential which is impressed upon the control electrode of discharge device V_2 from the source of reference potential is preferably square wave in form as shown in Fig. 2 and is of the frequency which is desired in the utilization circuit connected to the system. The amplitude of the square wave reference potential is preferably such that during the negative peaks thereof electron discharge device V_2 is cut off, and during the positive peaks V_2 draws control electrode current. Electron discharge devices V_1 and V_2 are so arranged and common cathode resistor 1 has such resistance value that the action of device V_2 , on the negative and the positive peaks respectively of the reference potential, is, alternately, first, to permit V_1 to

45

50

55

draw anode current through potentiometer 3 in accordance with the unidirectional input control potential, and, second, to bias device V₁ to cut-off regardless of the amplitude and polarity of the unidirectional control potential applied to its control electrode.

The common cathode resistor 1 is preferably of such resistance value as to provide correct Class A operation of discharge device V₁ when the input control potential is zero. It is desirable also that the input control potential impressed upon the control electrode of discharge device V₁ be limited to a range which insures a suitable amount of linearity between anode current and control electrode potential in that portion of the operating cycle during which device V₁ is drawing anode current.

The arrangement of the potentiometer 3 and discharge device V₂ is thus such that the anode current drawn by the latter discharge device is permitted to flow through a portion, as 8, of the potentiometer during the positive peaks of the square wave reference potential. By suitable selection of the point at which the anode of device V₂ is tapped into the potentiometer, the output alternating potential of the system may be made zero for any chosen value of the unidirectional input control potential impressed upon device V₁. For usual operation of the system it is desirable that normal adjustments be such that the output alternating potential is zero when the unidirectional input control potential is zero.

Operation of the system will be better understood by reference to Fig. 3 considered in connection with Figs. 1 and 2.

Referring, first, particularly to Fig. 3(a) which illustrates the case of zero unidirectional input potential and zero alternating output potential, designating the anode-cathode current of electron discharge devices V₁ and V₂ respectively as I_{PV1} and I_{PV2} and the resistance value of potentiometer sections 8 and 9 respectively as R₈ and R₉, let it be assumed that the unidirectional control potential on the control electrode circuit of discharge device V₁ is zero and that the output alternating potential of the system is also to be made zero. Then, when the square wave reference potential impressed upon the control electrode of discharge device V₂ is at its negative peak value as designated by portion 11 of curve 12, Fig. 2, the latter discharge device is cut off, no anode current from device V₂ flows in the common cathode resistor 1 and therefore electron discharge device V₁ is not biased to cut-off but draws, through both potentiometer sections 8 and 9 in series, the normal current which corresponds to zero value of the unidirectional input potential.

Under these conditions the potential drop between point 5, the potential of which is represented by the line 13 of Fig. 3(a), point 4 which in the arrangement illustrated in Fig. 1 is at the potential of the positive terminal of the anode supply source, is (I_{PV1}) (R₈+R₉).

When, next, the square wave reference potential changes from its negative to its positive peak value as designated by portion 14 of curve 12, Fig. 2, the electron discharge device V₂ then becomes conductive, its anode current flows in the common cathode resistor 1, and electron discharge device V₁ becomes biased to cut-off. Under these conditions, although V₁ is cut off and no current flows in section 9 of potentiometer 3, a flow of current occurs in the potentiometer section 8 which is included in the anode-cathode circuit of V₂. Electron discharge devices V₁ and V₂ are so se-

lected and arranged, V₂ being preferably a device of higher rating than V₁, and the section 8 of potentiometer 3 determined by the point 7, at which the anode of V₂ is tapped therein is caused to be of such resistance value, that the potential drop (I_{PV2}) (R₈) across the section 8 is made substantially equal to the before-mentioned potential drop (I_{PV1}) (R₈+R₉), across the entire potentiometer 3, which was the drop obtained when the square wave reference potential was at its negative peak.

Since, when device V₂ is conducting but device V₁ is cut off and no current flows in potentiometer section 9, the potential across section 8, or between points 4 and 7, is substantially that across both sections 8 and 9, or between points 4 and 5, therefore, under the condition of positive peak value of the square wave reference potential impressed upon the control electrode circuit of V₂, the potential of point 5, represented by the line 15 of Fig. 3(a), remains substantially the same as represented by line 13.

Therefore when the unidirectional input control potential is zero and the potential drop through the potentiometer 3 and its section 8 is equalized for both negative and positive peaks of the square wave reference potential by suitable selection of the tapping point 7, no alternating component appears in the potentiometer potential across points 4 and 5 and the potential of the alternating utilization circuit is zero.

Referring, secondly, particularly to Fig. 3(b) which illustrates the case of a positive unidirectional input control potential, assuming the same values as before for I_{PV1}, I_{PV2}, R₈ and R₉ and the same characteristics for the square wave reference potential 12, Fig. 2, impressed upon the input circuit of device V₂, let it be assumed that the unidirectional control potential supplied to the control electrode circuit of V₁ is changed from zero to a given positive potential. Then when the square wave reference potential impressed upon the control electrode circuit of V₂ is at its negative peak value the electron discharge device V₂ is as before cut off and the tube V₁ is conducting. But since the unidirectional control potential has been changed in the positive direction from zero to a given substantial value, the anode current of V₁ is increased during the conducting period and the potential drop in potentiometer 3 correspondingly increases, the potential of point 5 in Fig. 3(b) being represented for example by the line 16 of the latter figure.

When, however, the square wave reference potential impressed upon the input circuit of V₂ changes to its positive peak value, then, as before, V₂ becomes conductive, V₁ is cut off, and the potential drop across the section 8 of potentiometer 3 remains at its previously assumed value, (I_{PV2}) (R₈). The potential of point 5 represented by the line 17 of Fig. 3(b) thus remains the same as in the case of zero input control potential illustrated in Fig. 3(a).

Therefore, as represented by curve 18 of Fig. 3(b), when, in the system originally adjusted for zero unidirectional input control potential and zero alternating output potential, the input unidirectional control potential is adjusted to a suitable positive value, an alternating utilization potential is produced having the same frequency as that of the alternating reference potential.

Referring, thirdly, particularly to Fig. 3(c) which illustrates the case of a negative unidirectional input control potential, assuming the same

circuit characteristics in general as for the cases illustrated in Figs. 3(a) and 3(b), when the unidirectional control potential impressed upon the input circuit of V_1 is made negative then the anode current of V_1 during the conducting period is decreased instead of increased relatively to its value when the unidirectional control potential was zero. The potential drop in potentiometer 3 is correspondingly decreased, the potential of point 5 being represented by the line 19 of Fig. 3(c). However, during the period, corresponding to the positive peak 14 of the reference potential, when V_1 is cut off and V_2 is conducting, the potential drop across section 8 of potentiometer 3 remains again at its previously assumed value (I_{P2}) (R_8) and the potential of point 5, represented by the line 20 of Fig. 3(c), again remains the same as in the zero input control potential case illustrated in Fig. 3(a).

Therefore, as represented by curve 21 of Fig. 3(c), when in the system wherein the unidirectional input and the alternating output were both zero, the unidirectional input control potential, is given a negative value, an alternating utilization circuit potential is produced having the same frequency as that of the reference potential and opposite in phase to that of the utilization circuit potential produced when the unidirectional input control potential had a positive value.

In the arrangement of my invention illustrated in Fig. 1 the utilization circuit is described as connected directly across the potentiometer 3, the output potential being in phase with the reference potential for positive values of the unidirectional control potential and in opposite phase for negative values of the control potential. Other connection arrangements may be made, however. For example, the utilization circuit may be connected across point 5 and ground instead of across point 5 and point 4, which is at the potential of the anode current source.

While not entirely essential, because of non-linearity of electron discharge devices it is highly desirable in a system in accordance with my present invention that, as hereinbefore set forth square waves be employed as reference potential, since no waveform distortion is produced by nonlinear circuit elements when the system is operating on square waves. The reference potential may be constituted by square waves of any suitable frequency and of any desired pulse width.

In a typical system in accordance with my present invention circuit elements and constants may be substantially as follows:

Resistor 1—2000 ohms

Resistor 10—1 megohm

Potentiometer 3—10,000 ohms

Discharge device V_1 — $\frac{1}{2}$ of type 6SL7GT

Discharge device V_2 — $\frac{1}{2}$ of type 6SN7GT

Unidirectional input potential—+2 to -2 volts

Alternating reference potential—Square topped waves, 30 volts minimum (peak to peak)

Alternating output potential—+10 to -10 volts (peak to peak)

Capacitor 2—Depends on frequency of alternating potential

Capacitor 6—Depends on frequency of alternating potential

My invention has been described herein in particular embodiments for purposes of illustration.

It is to be understood, however, that the invention is susceptible of various changes and modifications and that by the appended claims I in-

tend to cover any such modifications as fall within the true spirit and scope of my invention.

What I claim as new and desire to secure by Letters Patent of the United States, is:

- 5 1. In combination, an electron discharge device having an output circuit including an impedance and an input circuit adapted to have a unidirectional potential impressed thereon, a second electron discharge device having an output circuit including a portion of said impedance and an input circuit adapted to have an alternating reference potential impressed thereon, and means including said second-named discharge device for causing said first-named discharge device to become alternately conducting and non-conducting in response to said reference potential, whereby an alternating current component is produced in said first-named output circuit.
- 10 2. In combination, an electron discharge device having an output circuit including an impedance, a second electron discharge device having an output circuit including a portion of said impedance and an input circuit adapted to have an alternating reference potential impressed thereon, a common bias means included in said output circuits, and means including said second-named discharge device and said bias means for causing said first-named discharge device to become alternately conducting and non-conducting in response to said reference potential.
- 15 3. In combination, a first and a second electron discharge device each having a control electrode, an anode and a cathode, a source of operating potential, a common cathode resistor for said discharge devices connected between the negative terminal of said source and said cathodes, a potentiometer included in series with said source and the anode-cathode circuit of said first device, means to include a portion of said potentiometer in series in the anode-cathode circuit of said second device, a source of variable unidirectional control potential connected to the control electrode-cathode circuit of said first device, and a source of alternating reference potential connected to the control electrode-cathode circuit of said second device whereby alternating potential having the frequency of said reference potential is produced across said potentiometer having one phase or the opposite phase dependent upon the value of said variable unidirectional potential.
- 20 4. In combination, a source of variable steady unidirectional control potential, a source of alternating reference potential, a utilization circuit, and means for producing in said circuit an alternating potential of the frequency of said reference potential and of amplitude and phase determined in accordance with said control potential, said means including an electron discharge means having an output impedance connected to said utilization circuit, means including a second electron discharge means for determining the conducting periods of said first-named discharge means in response to said reference potential, said second electron discharge means being in series with a portion of said output impedance to determine the potential thereon when said first device is nonconducting,
- 25 5. In combination, an electron discharge device having an output circuit including an impedance and an input circuit adapted to have a unidirectional potential impressed thereon, a second electron discharge device having an output circuit including a portion of said impedance and an input circuit adapted to have an alternating reference potential impressed thereon, and means including said second-named discharge device for causing said first-named discharge device to become alternately conducting and non-conducting in response to said reference potential.
- 30 6. In combination, an electron discharge device having an output circuit including an impedance, a second electron discharge device having an output circuit including a portion of said impedance and an input circuit adapted to have an alternating reference potential impressed thereon, a common bias means included in said output circuits, and means including said second-named discharge device and said bias means for causing said first-named discharge device to become alternately conducting and non-conducting in response to said reference potential.
- 35 7. In combination, a first and a second electron discharge device each having a control electrode, an anode and a cathode, a source of operating potential, a common cathode resistor for said discharge devices connected between the negative terminal of said source and said cathodes, a potentiometer included in series with said source and the anode-cathode circuit of said first device, means to include a portion of said potentiometer in series in the anode-cathode circuit of said second device, a source of variable unidirectional control potential connected to the control electrode-cathode circuit of said first device, and a source of alternating reference potential connected to the control electrode-cathode circuit of said second device whereby alternating potential having the frequency of said reference potential is produced across said potentiometer having one phase or the opposite phase dependent upon the value of said variable unidirectional potential.
- 40 8. In combination, a source of variable steady unidirectional control potential, a source of alternating reference potential, a utilization circuit, and means for producing in said circuit an alternating potential of the frequency of said reference potential and of amplitude and phase determined in accordance with said control potential, said means including an electron discharge means having an output impedance connected to said utilization circuit, means including a second electron discharge means for determining the conducting periods of said first-named discharge means in response to said reference potential, said second electron discharge means being in series with a portion of said output impedance to determine the potential thereon when said first device is nonconducting,
- 45 9. In combination, an electron discharge device having an output circuit including an impedance and an input circuit adapted to have a unidirectional potential impressed thereon, a second electron discharge device having an output circuit including a portion of said impedance and an input circuit adapted to have an alternating reference potential impressed thereon, and means including said second-named discharge device for causing said first-named discharge device to become alternately conducting and non-conducting in response to said reference potential.
- 50 10. In combination, an electron discharge device having an output circuit including an impedance, a second electron discharge device having an output circuit including a portion of said impedance and an input circuit adapted to have an alternating reference potential impressed thereon, and means including said second-named discharge device for causing said first-named discharge device to become alternately conducting and non-conducting in response to said reference potential.
- 55 11. In combination, an electron discharge device having an output circuit including an impedance and an input circuit adapted to have a unidirectional potential impressed thereon, a second electron discharge device having an output circuit including a portion of said impedance and an input circuit adapted to have an alternating reference potential impressed thereon, and means including said second-named discharge device for causing said first-named discharge device to become alternately conducting and non-conducting in response to said reference potential.
- 60 12. In combination, an electron discharge device having an output circuit including an impedance, a second electron discharge device having an output circuit including a portion of said impedance and an input circuit adapted to have an alternating reference potential impressed thereon, and means including said second-named discharge device for causing said first-named discharge device to become alternately conducting and non-conducting in response to said reference potential.
- 65 13. In combination, an electron discharge device having an output circuit including an impedance and an input circuit adapted to have a unidirectional potential impressed thereon, a second electron discharge device having an output circuit including a portion of said impedance and an input circuit adapted to have an alternating reference potential impressed thereon, and means including said second-named discharge device for causing said first-named discharge device to become alternately conducting and non-conducting in response to said reference potential.
- 70 14. In combination, an electron discharge device having an output circuit including an impedance, a second electron discharge device having an output circuit including a portion of said impedance and an input circuit adapted to have an alternating reference potential impressed thereon, and means including said second-named discharge device for causing said first-named discharge device to become alternately conducting and non-conducting in response to said reference potential.
- 75 15. In combination, an impedance, a source of variable unidirectional electromotive force, and means to produce across said impedance an al-

ternating potential of one phase or of opposite phase dependent upon the value of said unidirectional electromotive force, said means comprising means to pass unidirectional current of magnitude dependent on the magnitude of said variable electromotive force through said impedance to produce a potential between the terminals of said impedance, and means to produce current pulses through a portion of said impedance and to interrupt said unidirectional current 10 during said pulses.
